United States Patent Office.

JOHN W. FRY, OF ELIZABETH, NEW JERSEY.

Letters Patent No. 92,299, dated July 6, 1869.

IMPROVEMENT IN TELEGRAPH-INSULATORS.

The Schedule referred to in these Letters Patent and making part of the same.

To all whom it may concern:

Be it known that I, JOHN W. FRY, of Elizabeth, in the county of Essex, and State of New Jersey, have invented a certain new and improved Insulator for Telegraph-Wires; and I do hereby declare that the following is a full and exact description thereof, reference being had to the accompanying drawings, making part of this specification.

Figure 1 is a perspective view of my insulator, with a portion of wire attached.

Figure 2 is a side view with the jaws open, to receive or remove the wire.

Figure 3 is a side view with the jaws closed, and connected by a thumb-screw.

Like letters of reference indicate corresponding parts in all the figures.

The nature of my invention consists in an insulator for attaching telegraph-wires, which holds the wire by compression in an elastic and non-conducting substance, whereby it is firmly held, but in a manner which allows it to render as required, and prevents it from being broken by chafing, as when against a rigid metallic bearing, under the vibration to which it is subjected, and renders insulation more perfect.

An ordinary cast-iron spindle, A, is formed with a head, consisting of a fixed jaw, b, and a movable one, c, connected therewith by lugs, or hinges, or other joint that will enable it to be opened, to receive the wire, and securely locked, to retain it.

I prefer to cast the loose jaw with projections, which will form a hinged connection, whereby it opens for the purpose required, and, when closed, be secured by the pin e, fig. 1, which is readily formed of a bit of telegraph-wire.

These jaws receive a block of India rubber, f, preferably of cylindrical shape, and of a size larger than the space in which it is held, so that it is forcibly compressed when they are closed and fastened.

A radial incision, extending from the surface to the centre, receives the telegraph-wire d, which lies, as shown in the drawings, centrally embedded in the surrounding rubber. It is held therein by compression, with sufficient firmness, but with a grasp which yields, and allows it to "render" when tension is applied.

The wire may be as rapidly strung with this insulator as with any other. It is held, as it were, in a cushioned vise, which yields sufficiently to the flexion produced by wind and other causes, to prevent its breaking or chafing, as when it is supported in contact with a metal hook or other fastening. It is held by such close adhesion that no water can penetrate, and, by freezing, destroy insulation.

The spindle may be inserted in the socket G, ordinarily used, or connected directly to the arm of the telegraph-post.

The use of this insulator insures greater durability, by rendering the breakage of the wire less frequent, and a better working of the line, by its more perfect insulation, while the cost is not enhanced.

What I claim, and desire to secure by Letters Patent, is—

1. An insulator for telegraph-wires, formed to hold the wire by the compression of a surrounding cushion of India rubber, or other non-conducting and elastic substance, substantially as set forth.

2. An insulator, consisting of the spindle A, jaws b c, and India rubber f, arranged and operating substantially as and for the purpose set forth.

In witness whereof, I have hereunto signed my name, in the presence of two subscribing witnesses.

JOHN W. FRY.
